Primary Examiner—Caron D. Veynar*Assistant Examiner*—Sydney R. Buffalow(74) *Attorney, Agent, or Firm*—Wolf Block Schorr & Solis-Cohen LLP(57) **CLAIM**

I claim the ornamental design for a slat wall panel, as shown and described.

DESCRIPTION

FIG. 1 illustrates a fragmentary rear perspective view of a slat wall panel with an indeterminate length and height showing my new design;

FIG. 2 illustrates a fragmentary side view of a slat wall panel showing my new design, the left side view thereof being substantially the same as the right side view;

FIG. 3 illustrates a fragmentary front view of a slat wall panel showing my new design;

FIG. 4 illustrates a fragmentary top view of a slat wall panel showing my new design; and,

FIG. 5 illustrates a bottom view of a slat wall panel showing my new design.

The broken lines of FIGS. 1-5 are for illustrative purposes only and form no part of the claimed design.
